United States Patent Office

Des. 187,698
Patented Apr. 19, 1960

187,698

HAIR CLIPPER

Robert O. Ernest, Oak Park, Ill., assignor to Sunbeam Corporation, Chicago, Ill., a corporation of Illinois

Application October 13, 1958, Serial No. 52,935

Term of patent 14 years

(Cl. D22—3)

Fig. 1 is a front perspective view of a hair clipper embodying my new design;

Fig. 2 is a front elevational view thereof;

Figs. 3 and 4 are respectively left and right side elevational views;

Figs. 5 and 6 are top and bottom plan views;

Fig. 7 is a rear elevational view; and

Fig. 8 is an enlarged sectional view taken along the line 8-8 of Fig. 7, the same wavy configuration appears on the opposite side thereof.

I claim:

The ornamental design for a hair clipper, as shown and described.
